Primary Examiner — Eric Goodman*Assistant Examiner* — Jennifer Watkins(74) *Attorney, Agent, or Firm* — Luedeka Neely Group, PC(57) **CLAIM**

The ornamental design of a shoulder joint stabilizer, as shown and described.

DESCRIPTION

FIG. 1 is frontal perspective view of the shoulder joint stabilizer of my new design;

FIG. 2 is a front plan view of the shoulder joint stabilizer of my new design;

FIG. 3 is a rear plan view of the shoulder joint stabilizer of my new design;

FIG. 4 is a left side view of the shoulder joint stabilizer of my new design;

FIG. 5 is a right side view of the shoulder joint stabilizer of my new design; and,

FIG. 6 is a top plan view of the shoulder joint stabilizer of my new design.

The broken line portions of the drawings are included for the purpose of illustrating unclaimed structure and form no part of the claimed design.

1 Claim, 6 Drawing Sheets(56)
